APPAREL BELT ATTACHMENT

Myron Fleishman, 3471 Fenton Ave., New York, N.Y.

Filed Aug. 24, 1960, Ser. No. 61,871

Term of patent 7 years

(Cl. D17—1)

FIG. 2

FIG. 3

FIG. 1 is a perspective view of an apparel belt attachment showing my new design;

FIG. 2 is a view showing the cover of the article swung to open position;

FIG. 3 is a bottom plan view.

The pivoting plate bearing representations of playing cards is substantially planar on both faces, and the circular ornamentation on the back of the article has no depth.

I claim:

The ornamental design for an apparel belt attachment, as shown and described.
